2 SHEETS—SHEET 2.

UNITED STATES PATENT OFFICE.

SILAS H. LYNN, OF LONG BEACH, CALIFORNIA.

AERIAL AND MARINE CRAFT.

1,303,695.

Specification of Letters Patent. Patented May 13, 1919.

Application filed June 27, 1917. Serial No. 178,326.

To all whom it may concern:

Be it known that I, SILAS H. LYNN, a citizen of the United States, residing at Long Beach, in the county of Los Angeles and State of California, have invented new and useful Improvements in Aerial and Marine Craft, of which the following is a specification.

My invention relates to a form of combined aerial and marine vehicle capable of being propelled in the air or water and comprises certain features usually provided in heavier-than-air and lighter-than-air vehicles of well known form, together with new and novel features of my invention, which in their combined form, provide a vehicle of great utility in times of peace or war.

It is an object of this invention to provide propulsion means for my improved type of vehicle by means of which the same may be raised from the surface of the ground or a body of water in a substantially vertical or inclined plane, as may be desired or necessary, or propelled horizontally, according to the necessity of the occasion.

A further object is to provide a cab, or car on which the propulsion and controlling mechanism may be supported and having such a form that it may be adapted for use in the water; a gas bag being also provided for attachment to the cab so as to render the vehicle practically self sustaining in the air, and the gas bag being subdivided into a plurality of gas compartments, so that in the event of damage being done to any portion of the bag, for any reason or by any cause, the remainder of the bag will remain intact and capable of supporting the vehicle in the air.

A further object is to provide a plurality of basket like propellers on opposite sides of the vehicle having thin metallic blades and strap braces therefor and supported, preferably in inclined planes, and capable of operation for changing the inclination for changing the direction of movement of the vehicle accordingly.

A further object is to provide a plurality of transversely disposed planes at the sides of the vehicle and capable of being opened and closed, at will, for lending buoyancy to the vehicle and changing the angle of flight. Other objects may appear as the description progresses.

Referring to the drawings, in which simi-

lar characters of reference are employed for indicating the same or like parts, Figure 1 is a plan of the craft with the cab and operating mechanism shown in full lines and the gas bag and planes in broken lines, certain of the parts being omitted for clarity of illustration. Fig. 2 is an elevation of the same, partly in section. Fig. 3 is a transverse sectional elevation of the vehicle. Fig. 4 is an enlarged elevation of one of the propeller driving shafts, gears and mounting, which is typical of all of such elements. Fig. 5 is a plan of the same. Fig. 6 is a side elevation of the worm gearing employed for changing the inclination of each of the propellers.

Fig. 7 is a transverse elevation, partly in section, of the steering mechanism and supports therefor. Fig. 8 is a side elevation of the same. Fig. 9 is a sectional plan of the same on the line 9—9 of Fig. 8, and Fig. 10 is a sectional plan of the same on the line 10—10 of Fig. 7. Fig. 11 is an enlarged side elevation of one of the transverse plane operating cranks and connections. Fig. 12 is a side elevation of the crank operating rod and pulley, by means of which all of the planes on each side of the vehicle are moved simultaneously, and Fig. 13 is an end elevation of the operating pulley therefor and support, typical of both sides of the vehicle. Fig. 14 is a front elevation of one of the propellers. Fig. 15 is an enlarged view of one of the supports for the side planes.

The structure of my improved craft includes primarily, a gas bag 1, preferably of the usual cigar shape, the cab or boat 2 adapted to be suitably secured to the frame of the gas bag, the transversely disposed side planes 3 arranged in series on both sides of the craft in planes substantially central with the gas bag, and a rudder which is adapted to guide the vehicle in its progress in any desired direction.

The gas bag 1 is preferably subdivided into a plurality of compartments 5 with partitions 6 of fabric or other material therebetween and suitably attached to the transverse ribs 7. In the plane of the major diameters of the bag 1 suitable encircling ribs 8 are provided which may be suitably attached at the intersections to the transverse ribs 7 so as to provide a rigid frame for the outer fabric 9 of the bag, the ribs

100

105

110

8 being preferably on the exterior of the bag. Suitable gas valves 10 may also be provided for each of the compartments in the bag, for filling or evacuating the several compartments independently of each other.

The car 2 partakes as nearly as possible of the design of a boat, the ends being curved upwardly and inwardly, as shown, for minimizing the resistance when used in the water, and the uppermost portions of the ends may be suitably secured to the frame of the gas bag 1. The sides of the car have inwardly curved upper portions 11 forming a restricted opening in the top of the car or boat above the bottom and serving to direct the water which may be thrown against the sides outwardly therefrom during the forward movement of the boat. The end portions of the car or boat have covers 12 extending in the direction of the center of the car, beneath which, storage and sleeping compartments may be provided for the operators of the vehicle; also sufficient space is here provided for the storage of an ample supply of fuel for long journeys.

Standards 13 of solid, ribbed or tubular formation, are provided at the sides of the vehicle, the lower ends thereof being secured to the side portions 11 by means of suitable fittings 14 and the upper ends being suitably secured to the ribs 8 of the gas bag 1. The ribs of the gas bag are suitably braced by means of guy wires 16 and the standards 13 are similarly braced by means of wires 15, thus providing a rigid structure for the vehicle. Wheels 17 are provided on the exterior of the bottom of the car and supported in suitable brackets 18, thus serving to permit the movement of the vehicle over the surface of the ground.

The transverse planes 3 are pivotally supported at their forward sides on tubular arms 19 which have relatively long bearings 20 attached to the lower sides of the gas bag frame and these planes are arched, as shown, and substantially overlap at the ends so that when the free ends thereof are raised the free ends of each of the planes will closely fit against the fixed ends of the adjacent planes, thus providing a continuous plane on each side of the vehicle for supporting the vehicle in a true horizontal plane. An operating crank 21 is provided for each of the planes 3 with an arm 22 formed thereon and adapted to be pivotally and slidably attached to the inner side rib 23 of the plane frame by means of a pin or screw 24, and a relatively short arm 25 which is attachable to a longitudinal rod 26 common to all of the operating cranks. The cranks 21 are pivotally supported on the lower side of the gas bag frame in bearings 27 and the arrangement of the cranks is such that when the operating rod 26 is moved forward of the vehicle, all of the

planes 3 will be opened, as shown in Fig. 2, and when moved rearwardly the planes will be closed for forming a continuous plane, as stated.

The rod 26 on each side is moved longitudinally by means of a cable 28 operating around a pulley or drum 29 supported on a transverse shaft 30 journaled in bearings 31 and 32 attached, respectively, to the foremost of the standards 13 and the gas bag frame. The ends of the cable 28 are attached to collars 33 and 34 held on the rods 26 by set screws, or otherwise, one of the collars being on the opposite side of the pulley from the other, and the movement of the pulley in one or the other direction serving to move the rod 26 in a corresponding direction, for opening and closing the planes 3.

The plane operating shafts 30 are provided with pulleys or sprockets 35 which are driven by means of a belt or chain 36, in each case, connected with a driving pulley or sprocket 37 carried by a shaft 38 journaled in bearings 39 and 40 attached to the forward cover of the car. Each of the shafts 38, which are transversely alined, has a bevel gear 41 carried on the inner end and adapted to be operated by means of a common bevel gear 42 carried on a relatively short longitudinal shaft journaled in a bearing 43 and on the outer end of which is a hand wheel 44. Thus the turning of the wheel 44, rotates the shafts 38, by means of the bevel gears described, and the upper shafts 30 are rotated to correspond by means of the pulleys and belts described, and the opening and closing of the planes on both sides of the vehicle simultaneously accomplished by means of a single operating wheel.

The vehicle is steered in its flight or movement by means of the rudder comprising a pair 45 of horizontal and a pair 46 of vertical vanes disposed in planes paralleling the longitudinal axis of the car. The rudder is supported for universal movement relative to the car in a ball and socket joint 47 attached to the rear of the car 2. Cables 48 and 49 are attached to and lead from the corners of the vanes 45 to the interior of the car, and similar cables 50 and 51 extend from the vanes 46 to the interior, suitable pulleys 52 being provided between the bottom 53 and false bottom 54 of the car over which the cables operate and then inner ends of the cables are connected with the steering mechanism in the manner hereinafter described.

A steering column 55 of tubular cross section is provided with an enlarged lower housing 56 having trunnions 57 on the sides thereof which are journaled in suitable bracket bearings 58 supported on the floor of the car. A vertical shaft 59 is revolvably supported in the column 55 and is provided within the housing 56 with a drum 60 which is centrally held relative to the axis of the

trunnions and which is adapted to receive two or more turns of the cables 48 and 49 attached to the vanes 45 of the rudder.

The column 55, together with the drum 60 5 and steering shaft 59, is movable about the axis of the trunnions 57 in a vertical plane paralleling the longitudinal center line of the car and the cables 50 and 51 leading from the vanes 46 of the rudder are connected, respectively, by means of an eye 61 and an arm 62, 10 to the column 55 at points equally distant from the axis and above and below, as shown in Figs. 7 and 8. One of the bearings 58 has a quadrant 63 formed thereon with a plurality of notches 64 formed therein and 15 adapted to be engaged by a latch or pawl 65 held on the lower end of a vertically movable rod 66 carried in suitable bearings formed on the side of the column and provided with a 20 spring 67 for maintaining the engagement between the pawl 65 and the quadrant 63. The locking rod 66 is operated by means of a yoke lever 68 pivotally held on the column near the top.

25 Thus the column 55 and the attached mechanism may be moved pivotally, backward and forward, when the locking rod 66 is released from the quadrant, for the purpose of moving the rudder in a vertical plane 30 to change the ascending or descending angle of the vehicle, by means of the cables 50 and 51. The shaft 59 has a hand wheel 69 at the top by means of which the shaft and drum 60 may be turned in the column for moving 35 the rudder laterally for changing the lateral angle of the vehicle. It will be obvious that the universal action of the steering means described provides an efficient method of directing the movement of the vehicle at 40 any angle and eliminates the necessity for two separate rudders and steering wheels, such as are sometimes provided.

In the drawings a pair of motors 70 are 45 shown for propelling the vehicle in the air or on the water, but one or more than two may be used if necessary. As shown, each motor operates a countershaft 71 by means of sprockets or pulleys 72 and 73 placed respectively, on the countershaft 71 and the 50 crank shaft of the motor and connected by means of chains or belts 74. The counter-shafts are journaled at the ends in bearings 75 formed on brackets 76 supported in any suitable manner on one of stanchions or 55 standards 13 and in bearings 77 secured to the frame of the gas bag 1. A pair of transversely alined propeller shafts 78 are positioned in the vertical plane of the counter-shafts and the inner ends thereof are journaled in bearings 79 secured to the frame of the gas bag while the outer ends thereof are journaled in bearings 80 formed on and extending inwardly from the propeller yokes 81, as shown in Figs. 4 and 5.

60 65 Gears 82 are carried by the countershafts

71 and drive the shafts 78 by means of gears 83 thereon, thus providing means for operating the central set of propellers. The outer ends of the shafts 78 are provided with bevel gears 84 which mesh with and drive 70 bevel gears 85 attached to the inclined propeller shafts 86 which are journaled in bearings 87 and 88 on the opposite ends of the propeller yokes 81. The propellers 89 comprise a plurality of curved vanes 90 disposed 75 at angles relative to the axis of the propeller shafts and supported by means of braces 91 attached thereto and to the hubs 92.

The bearings 80 of the shafts 78 are pivotally held in lugs 93 formed on the brackets 80 76 and the inner ends thereof carry sectors 94 which mesh with and are adapted to be pivotally moved by worms 95 carried on the longitudinal shafts 96 which are journaled in bearings 97 formed on the brackets 76. 85 Motion is communicated to each of the other propellers on the opposite sides of the vehicle by means of a common driving shaft 98 journaled in each of the bearings 99 on brackets 76, and spiral gears 100 and 101 operably connect the shafts 98 with the transverse shafts 78. It should be understood 90 that each propeller unit is identical except for the provision of the primary driving means connected with the central set of propellers and motion is communicated to each set of propellers both forward and rearward of the central set by means of the shafts 98. Likewise, the worm shafts 96 are connected 100 with each set of propellers on their respective sides of the vehicle and one of the sectors 94 is provided in each case so that the movement of the worm shaft on one side of the vehicle will simultaneously move all of the propellers to a uniform degree, thus 105 changing their position from their lowermost diagonal plane as shown in Fig. 4, to a plane at angles thereto.

Each of the worm shafts 96 is provided 110 with an independent operating wheel 102 which is supported on a bracket 103 mounted on the forward end of the vehicle and has a pulley or sprocket 104 attached thereto which is connected by means of a chain or belt 105 with a similar pulley or sprocket 106 mounted 115 on shaft 96.

The propellers, when in their lowermost positions, as shown in Fig. 4, serve to raise the vehicle from the ground or surface of the water, but when the worm shafts 96 are 120 turned by means of the hand wheels 102 in one or the other direction, the inclination of the propellers is changed correspondingly and the propellers in such case serve to move the vehicle either forward or backward according to the angle and such angle of operation may be preserved for as long a time as may be desirable.

125 The structure shown and described discloses a practical and operative device, but 130

the same may be modified and changed in many respects without departing from the spirit or enlarging the scope of my invention. The principle employed in the operation of the various elements forming a part of this invention may be carried out successfully with the operating devices shown, or other devices of simpler or more elaborate character may be substituted therefor in order to provide a greater or less range of usefulness for the vehicle. The provision of two motors is desirable for the reason that in the event one of them should become disabled when the vehicle is in the air the other may be used for propelling the vehicle, or both may be used as hereinbefore described.

Having thus described my invention, what I claim is:

20 1. In an aerial and marine craft, a gas bag having a plurality of compartments formed therein, an external frame work extending horizontally therearound, a plurality of internal reinforcing ribs extending 25 around the periphery of said bag opposite said compartments, a plurality of stanchions attached to said frame work and depending therefrom, a car supported on the lower end of said stanchions, and a plurality of tilt- 30 able planes laterally disposed relative to said bag, and supported on said stanchions for regulating the flight of the craft.

2. In an aerial and marine craft, a gas bag having a plurality of compartments formed therein, an external frame work extending horizontally therearound, a plurality of internal reinforcing ribs extending around the periphery of said bag opposite said compartments, a plurality of stanchions 40 attached to said frame work and depending therefrom, a car supported on the lower end of said stanchions, and a plurality of tilt- able planes laterally disposed relative to said bag, supported on said stanchions for regulating the flight of the craft, and means for simultaneously tilting all of said planes.

3. In a craft of the character described, the combination with a car and a motor

therein, a gas bag supported above said car, a plurality of tilttable planes extending outwardly from each side of said gas bag, a drive shaft extending transversely of said car, a plurality of propeller shafts operably connected with said drive shaft, a propeller disposed at an oblique angle to and adapted to be operated by each of said propeller shafts, a longitudinal shaft on each side of the craft capable of operation for swinging said propellers bodily around the axes of their supports, and manually operable means for operating said longitudinal shafts.

4. In a craft of the character described, the combination with a car having a motor therein, a drive shaft extending transversely of said car, a plurality of propeller shafts 65 operably connected with said drive shaft, a propeller disposed at an oblique angle to and adapted to be operated by each of said propeller shafts, a longitudinal shaft on each side of said car capable of operation for 70 swinging said propellers bodily around the axes of their supports, and manually operable means for operating said longitudinal shafts.

5. In a craft of the character described, 75 the combination with a car having a motor therein, a drive shaft supported transversely on said car, a longitudinal shaft on each side of said car for operation by said drive shaft, a plurality of driven shafts operated by 80 each of said longitudinal shafts, a yoke support on each of said driven shafts, a propeller shaft carried by each of said supports at an oblique angle to and adapted to be operated by said driven shafts, a propeller 85 on each of said oblique shafts, and manually operable means for oscillating said supports, for the purpose described.

Signed at Los Angeles, in the county of Los Angeles and State of California, this 90 11th day of June, 1917.

SILAS H. LYNN.
